(57) **CLAIM**

The ornamental design for a “carbon fiber composite casing with an electromagnetic-wave penetrable area,” as shown and described.

DESCRIPTION

FIG. 1 is a perspective view of a carbon fiber composite casing with an electromagnetic-wave penetrable area showing our new design;

FIG. 2 is a top view thereof;

FIG. 3 is a front view thereof, the rear view being a mirror image;

FIG. 4 is a left side view thereof, the right side view being a mirror image; and,

FIG. 5 is a perspective view thereof, shown in environmental use.

The broken lines shown represent unclaimed subject matter and form no part of the claimed design.
